Attest.

United States Patent Office.

ARCHIBALD PERRY, OF RICHLAND, INDIANA, ASSIGNOR TO HIMSELF AND JACOB FISHER, OF SAME PLACE.

Letters Patent No. 97,958, dated December 14, 1869; antedated December 3, 1869.

IMPROVEMENT IN SAWING-MACHINE.

The Schedule referred to in these Letters Patent and making part of the same

To all whom it may concern:

Be it known that I, ARCHIBALD PERRY, of Richland, in the county of Rush, and in the State of Indiana, have invented certain new and useful Improvements in Sawing-Machines; and do hereby declare that the following is a full, clear, and exact description thereof, reference being had to the accompanying drawings, and to the letters of reference marked thereon.

The object of my invention is to provide a saw-mill that shall be light and portable in its construction, the mechanism of which shall be so arranged as to give greater strength to the movements of the saw, and yet require a less amount of steam to run it.

Figure 1 represents a side elevation of my machine.

Figure 2 is a section of the same.

Figure 3 is an end view of the saw, showing the manner in which it is attached to the frame.

Letter A represents the frame of my machine, which is provided, upon its top, with a track, B, upon which the carriage C, which brings the lumber up against the saw, is moved.

Attached to the driving-shaft is the wheel D, pivoted to which is arm E.

One end of this arm is attached to one side of the wheel D, while the other is secured to the rocking lever F, so that when the wheel is once set in motion, the arm communicates it to the lever.

This lever is balanced or hung upon the shaft G, and is of a triangular or harp-shape, as seen in fig. 2, having one of its corners attached to the lower end of the saw H, by means of a plate or clamp, so that when the lever is made to rock, it imparts a reciprocating motion to the blade.

Both ends of this saw are provided with clasps I, attached to the same side of the blade, which move up and down in slides, as seen in fig. 3. By having these clasps and slides on the same side of the saw, the blade cannot be made to vibrate, and is much more regular and even in its stroke.

Letter J represents an upright beam, one of which is on each side of the frame, and which have a cross-beam, extending from their tops, across from one side to the other.

Extending outward from this cross-beam is the head-block, to which the upper end of the saw is attached.

Upon the outer end of the shaft G, upon which the rocking lever is hung, there is placed a small crank, K, for the purpose of operating the lever L, which operates the feed-mechanism.

This lever is pivoted to the side of the upright beam J, and has its upper end slotted to a considerable distance down, so that the arm M, which is secured to it, can be moved nearer to or further from the centre of motion, whereby the length of its stroke is made longer or shorter, as the case may need.

Letter M is the arm, one end of which is attached

to the lever L, as already described, while the other is furnished with a clamp, N, sufficiently wide and large to clasp the top of the wheel O, and by means of which the said wheel is operated, so as to move the carriage C toward the saw.

In order to make the clamp N grasp the wheel, and hold it in its place, the spring P has been provided, one end of which is attached to the beam J.

Upon the same shaft as the wheel D, there is a second wheel or pulley, as seen in dotted lines in fig. 2, over which a belt, R, is passed, so as to communicate motion to the wheel S.

T is a friction-wheel, attached to the same shaft as the wheel S, and is used to reverse the motion of the wheel O, so as to move the carriage back from the saw. The outer part of the frame upon which this wheel T has its bearings, is only pivoted on to the main part, so that it can be moved up and down, in order to be brought in contact with the periphery of the wheel O.

One end of this movable bearing U is attached to the rod V, which passes up to the top of the frame, where it is secured to the lever W, by which this wheel T is brought into contact with the one O.

The carriage C is composed of two parts, which are united or formed together by means of the bar or beam X, as seen in fig. 2, the lower part of which is provided with a toothed rack, which is operated by the cog-wheel Y. This cog-wheel is attached to the same shaft as the wheel O, and is operated by it.

To the side of the beam J is secured a roller, h, over which a cord passes, so that the arm M can be lowered and raised.

On the inside of the beam J is placed the spring a, as shown in dotted lines in fig. 1, the lower end of which is secured to the clamp N by means of the cord c, so that after the arm M has moved the clamp to its full length, the spring a draws it back so as to take a new hold.

Pivoted to the cross-beam extending across the top of the frame, is the lever d, to the end of which are attached two cords, e and f.

In order to prevent the wheel from turning backward, after it has been propelled forward by the arm M, the brake g has been provided, which is hinged to the beam J, and is attached to the cord f.

The mode of operating my machine is as follows:

The motive-power is applied to the shaft upon which the wheel D is placed, and the motion being communicated to the rocking lever F, the saw is set in motion. The crank K, revolving, causes the lever L to oscillate, and this communicating motion to the arm M, the wheel O is slowly propelled around, and this causing the cog-wheel Y to revolve, which works in the toothed rack of the carriage, the object to be sawed is thus brought up to the saw.

As soon as the sawing-operation is completed, and

it is desired to move the carriage back, the cord at the opposite end of the lever *d* is pulled, and this operating on the two cords *e* and *f*, the clamp *N* and brake *g* are raised entirely clear from the wheel *O*. The lever *W* then being depressed, raises the friction-wheel *T* so as to come in contact with the wheel *O*, when the motion is at once reversed, and the carriage moved back.

Having thus described my invention, What I claim, and desire to secure by Letters Patent is—

1. The lever *L*, slotted or open at each end, in combination with the crank *K*, arm *M*, and clamp *N*, when used in the manner and for the purpose as specified.
2. The forked lever *L*, crank *K*, arm *M*, and clamp *N*, in combination with the rocking lever *F*, shaft *G*, crank *K*, pitman *E*, and wheel *D*, all constructed and operating substantially as set forth.
3. The arm *M*, so arranged and constructed as to be moved nearer to and further from the centre of

motion, in combination with the clamp *N*, springs *P* and *a*, and cord *c*, when used in the manner and for the purpose as specified.

4. The arrangement of the lever *d*, cords *e* and *f*, brake *g*, and arm *M*, when all are used in the manner and for the purpose as set forth.

5. The saw *H*, connected at the top and bottom to the slides *I* on the same side, and operated by the rocking lever *F*, all substantially as set forth.

6. The combination of the lever *L*, arm *M*, clamp *N*, springs *a* and *P*, cords *c*, *e*, and *f*, lever *d*, and brake *g*, all constructed and arranged to operate substantially in the manner and for the purposes herein set forth.

In testimony that I claim the foregoing, I have hereunto set my hand, this 5th day of March, 1869.

ARCHIBALD PERRY.
